UNITED STATES PATENT OFFICE.

WALTER J. FROST, OF KENOSHA, WISCONSIN.

VALVE-OPERATING MECHANISM FOR FLUSH-TANKS, &c.

964,098.

Specification of Letters Patent. Patented July 12, 1910.

Application filed September 1, 1909. Serial No. 515,689.

To all whom it may concern:

Be it known that I, WALTER J. FROST, a citizen of the United States, residing in the city of Kenosha, county of Kenosha, and 5 State of Wisconsin, have invented certain new and useful Improvements in Valve-Operating Mechanisms for Flush-Tanks, &c., of which the following is a specification.

This invention relates to improvements in 10 valve operating mechanisms for flush tanks, &c., of that general character in which the flushing tank is brought into operation by moving a lever or handle.

Among the salient objects of the invention 15 are to provide a construction in which movement of the handle in either direction is equally effective in operating the mechanism; to provide an improved leverage mechanism in which a double cam connection to move with the handle acts positively upon either of two interconnected gear segments and so actuates the valve proper; to provide a construction so designed and organized that the main parts thereof may be 20 made of stampings, thus securing both economy and accuracy of manufacture; to provide a construction so organized that it is adjustable to walls of varying thickness, thus enabling a standard size to be adapted 25 to tanks of various makes; to provide a mechanism the parts of which are interconnected to form a unitary attachment which may be applied to a flushing tank as 30 an entirety, thus minimizing the care necessary to apply it but nevertheless insuring 35 reliability of operation; to provide novel means for securing the handle to the actuating shaft; to provide a construction which is of neat and finished appearance when applied, and in general to provide an improved mechanism of the character referred 40 to.

The invention consists in the matters hereinafter described and more particularly 45 pointed out in the appended claims.

In the drawing, Figure 1 is a sectional view through a tank showing an inner wall of the latter to which the invention is applied; Fig. 2 is a vertical axial section on 50 line 2—2 of Fig. 1; Fig. 3 is a sectional view of the leverage mechanism taken just inside of the yoke plate and showing the cam and leverage mechanism; Fig. 4 is a

sectional detail showing the means of securing the handle to the cam shaft; Fig. 5 55 is a fragmentary, perspective view of a part of the valve-lifting lever, showing more particularly the manner in which the latter is bent.

In the drawing 1 designates a flush tank 60 which may be of any suitable or usual type.

The attachment constituting a preferred embodiment of the present invention is applied to the wall of the tank so that the main operative parts are within the tank while 65 the handle is arranged outside the latter, as usual. Through the wall 2 of the tank is arranged to extend a combined bracket 3 and integral bushing 3'; the bracket being arranged to rest against the interior of the 70 tank wall and being conveniently clamped against rotary movement by means of a nut 18 applied to the threaded protruding portion 17 of the bushing. Through the bushing is arranged to extend a cam shaft 4 75 which is provided with a spline groove 10 extending throughout a considerable part of its length, and at its outer end with a reduced extension 11 to which a handle 12 is attached, in a manner hereinafter described. 80

Upon the cam shaft is mounted a double wing cam 13 which has an integral tongue 14 engaging the spline groove 10 and two divergently disposed cam extensions or wings 15. The lower angles of the bracket 85 3 carry outstanding pivot studs conveniently made in the form of hollow rivets 6, and upon these pivoted studs is mounted a valve-lifting lever 9, terminating at its inner end in a gear segment 8, and a gear segment 7 90 which intermeshes with the segment 8. In order to properly confine these parts and the cam 13 in the same plane, a yoke plate 5 is mounted upon the outer ends of the studs 6 and apertured to fit over the end of shaft 95 4; this yoke plate being rigidly secured by upsetting the ends of the studs 6, as seen in Fig. 1. The cam extensions 15 of the cam, and the upper edges of the gear segments are suitably shaped to coöperate in such a 100 manner that as the handle 12 is oscillated in either direction one gear segment or the other will be depressed positively, and since the segments are interconnected, it follows that the valve-actuating lever 9 will be 105 raised. The free end of lever 9 actuates any

suitable valve 23 coöperating with the outlet pipe 24 of the tank; the valve body being connected with the lever 9 by means of a link 22 pivoted to the lever, as indicated 5 at 25.

The outer end of the bushing and the nut thereon are desirably inclosed by the escutcheon plate 16 suitably secured to the outer wall of the tank and centrally apertured to 10 receive the reduced extension 11 of the cam shaft. In conjunction with the handle which is attached to the cam shaft, the escutcheon plate confines the cam shaft against endwise movement.

15 The handle 12 is attached to the cam shaft in a novel and peculiar manner now to be described: The attached end of the handle is provided with a lateral socket 12' which fits accurately upon the extension 11 and is 20 also provided with an intersecting axial bore 19 the lower end of which is internally threaded to receive a screw key 20. The extension 11 of the cam shaft is correspondingly apertured to receive the key, and the latter is shouldered as indicated at 21 to seat against the upper end of the handle. By means of this construction the handle is keyed rigidly against both rotary and lateral movement relatively to the cam shaft; the 25 securing means is apparently wholly concealed, since the head of the key is made to resemble a continuation of the handle and the construction is such that the parts may be constructed with great accuracy and economy.

It will be noted that the bushing is threaded throughout a considerable part of its length so that the nut 18 may be adjusted thereon to clamp walls of varying thickness, 40 and that the hollow escutcheon plate is of such construction as to accommodate the end of the sleeve throughout a fairly wide range of adjustments. The cam-plate being adapted for engagement with any part of the 45 grooved portion of the shaft 4, and being confined by the yoke plate, the attachment may be applied equally well to thick or thin walls. The cam shaft is purposely made of a sufficient length to accommodate walls of 50 minimum thickness. It will, of course, be understood that the mechanism is not limited in its use to this particular application, but is susceptible of adaptation to a wide range of uses.

55 I claim:

1. In a leverage mechanism, the combination of a bearing support, a rocking member mounted therein, a double-winged cam moving with said rocking member, two cam- 60 actuated members having hinge-like connections with each other pivotally mounted with their flexing connections opposite a point between the two wings of the cam,

and a handle for actuating said rocking member.

2. In a leverage mechanism, the combination of a bearing support, a shaft journaled therein, a double-winged cam upon said shaft, a lever pivoted between its ends and terminating in a segment mounted adjacent to and in coöperative relation with one wing of said cam, and a coöperating segment intergeared with the first and pivotally mounted in coöperative relation with the other wing of said cam.

75 3. In a leverage mechanism, the combination of a bearing sleeve, a rock shaft extending therethrough, a double-winged cam fixed upon said rock-shaft, a bracket carried by said sleeve, a pair of intergeared 80 segments pivotally mounted upon said bracket in coöperative relation to the cam, a lever extension connected with one of said segments, and a handle connected with the rock-shaft.

85 4. In a leverage mechanism, the combination of a bearing sleeve, a rock-shaft extending therethrough, a double-winged cam fixed upon said rock-shaft, a bracket carried by said sleeve, a pair of intergeared 90 segments pivotally mounted upon said bracket in coöperative relation to the cam, a yoke mounted upon the pivot-studs overlying both the segments and the winged cam and confining said elements in the same 95 plane, a lever extension connected to one of said segments, and a handle connected with the rock-shaft.

100 5. In a leverage mechanism, the combination of a bearing sleeve, a rock-shaft extending therethrough, a double-winged cam fixed upon said rock-shaft, a bracket carried by said sleeve, a pair of intergeared segments pivotally mounted upon said bracket in coöperative relation to the cam, a yoke mounted upon the pivot-studs overlying both the 105 segments and the winged cam and confining said elements in the same plane, a lever extension connected to one of said segments, a supporting wall through which said sleeve extends, means for holding said sleeve fixedly within said wall, and an escutcheon-plate fitted over the end of the rock-shaft at that side of the wall remote from the cam-mechanism, and confining the rock-shaft against endwise movement in one direction, and a handle applied to said rock-shaft outside said escutcheon-plate and limiting the rock-shaft against endwise movement in the opposite direction.

110 6. The combination with a flushing tank having a discharge outlet, of a valve therefor, and mechanism for operating said valve comprising a manually actuated rock shaft, a double cam carried thereby, intergeared 115 members actuated by said cam, and oper-

ative connections between said gear members and valve.

7. The combination with a main frame, of a bracket mounted thereon and having a bearing sleeve, said sleeve projecting through said main frame and screw threaded at its outer end, a clamping nut for said threaded end, a shaft journaled in said sleeve and

having a spline groove, a cam upon said shaft and having a lug sliding in said groove, 10 leverage mechanism operated by said cam, and means for operating said shaft.
